(57) **CLAIM**

The ornamental design for a mobile power bank, as shown and described.

DESCRIPTION

FIG. 1 is a perspective view of a mobile power bank showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom right perspective view thereof, with the left side strip, which is illustrated in broken lines, shown in an open position; and,

FIG. 9 is a bottom left perspective view thereof, with the right side strip, which is illustrated in broken lines, shown in an open position.

The dashed broken line showing of portions of the mobile power bank forms no part of the claimed design. The dot-dash broken lines define the bounds of the claimed design and form no part thereof.
